UNITED STATES PATENT OFFICE.

WILLIAM F. SHAFFER AND BLAKE CRUTCHFIELD, OF JACKSON, TENNESSEE.

LATCH FOR RAILWAY-CAR COUPLINGS.

Application filed April 1, 1922. Serial No. 548,611.

To all whom it may concern:

Be it known that we, WILLIAM F. SHAFFER and BLAKE CRUTCHFIELD, citizens of the United States, residing at Jackson, in the county of Madison and State of Tennessee, have invented certain new and useful Improvements in Latches for Railway-Car Couplings, of which the following is a specification.

10 The present invention relates to couplings for railway cars and more particularly to latches for the keys used to secure the drawheads or coupling hooks.

Couplings of this class are commonly supplied with broad flat cross keys for securing the drawhead or hook and a cotter pin for holding the key in place. These cotter pins are apt to work loose unless they are inserted with great care, or they 15 might be absent altogether through negligence of the workman assembling the coupling. This may often be the cause of serious accidents and one object of the present invention is to provide a perfectly safe 20 latch, which automatically locks the key, when the latter is inserted in position, so that no special care need be taken by the 25 workmen.

One embodiment of the invention is illustrated in the accompanying drawing; and

Figure 1 is a plan view of a drawhead with its key and the latch removed;

Figure 2 is a side elevation of Figure 1;

Figure 3 is a transverse section of Figure 2 along line 3-3 of Figure 2;

Figure 4 is a top plan view of the latch in inoperative position;

Figure 5 is an elevation seen in the axial direction of its trunnions and also in unlocked position; and

Figure 6 is a cross section on lines 6-6 of Figure 1 showing the key and the latch in locked position.

Numeral 10 represents a drawhead or hook assembled in its bearing 11 on a railroad car with a key 12 inserted through the usual aperture provided in the drawhead. This key is of rectangular cross section with flat top 13 and bottom 14 and parallel side edges 15. It is provided with a turned up end 16 forming a stop in one direction and an aperture 17 at the other end, an inner face 18 of which is parallel to the side 19 of the bearing or in other words the distance between the face 18 and the stop 16 on the key is approximately the

same or slightly more than the width of the bearing 11. The seat 9 for the key in bearing 11 is of the same cross section as the key.

In the aperture 17 is inserted an automatic latch which is provided with a pair of trunnions 21 in axial alinement and for which corresponding bearings 22 are furnished in the key. The latch 20 has an upper flat end 23 and a lower flat end 24 both of the same thickness as the key 12, so that when the latch is in inoperative position as seen in Figure 5, the side faces of the ends 23 and 24 will become flush with the top and bottom sides 13 and 14 of the key 12.

One end 24 of the latch is made heavier than the other end 23 in order that the latch may hang perpendicularly as seen in Figure 6 when in locking position. For this purpose the end 24 is beveled as at 25 so as to make it broader than the upper end 23 and it is also somewhat longer counting from the axis of the trunnions 21 than the other end. The extremity of the lower end 24 is also beveled as at 26 for the purpose of forming a stop against the beveled face 27 in the aperture 17 of the key. In this manner, when the latch is turned in the direction of arrow X in Figure 6 preparatory to removing the key 12, the side 28 of the latch will become flush with the top side 13 of the key, when the latch is in the position indicated in Figure 5. This facilitates assembling and removal of the latch in the aperture 17 in the key 12.

A pair of lugs 29 are provided one on each side of the latch and these lugs have a beveled face 30 as indicated in Figures 4 and 6 for the purpose that if the latch gets in crossways as regards the key, it will be impossible for the key to work out.

The latch operates in the following manner:

When the drawhead 10 is assembled in its bearing 11 and its key seat registers with the key seat 9 in the bearing 11 the key is inserted into these seats with the latch removed, as shown in Figure 1. The key will now readily slip through the key seat and when the key is pushed home in the seat the latch 20 is dropped into the aperture 17 with its beveled face 26 approximately perpendicular. Directly the latch has been released it will turn automatically actuated by its preponderance into the position shown in Figure 6 with the end

23 upwards and end 24 downwards and as the total length of the latch in the perpendicular direction is greater than the height of the seat in the bearing 11, the latch will 5 naturally lock the key in its seat without any extra precaution being taken by the workmen. Should subsequently the latch turn out of this position, actuated by shocks or vibrations during travel and take the position indicated in Figure 5, it will still prevent the key from coming out, as the lugs 29 will now extend above and below the key seat 9 in the bearing 11.

Having thus described the invention, what 15 is claimed as new is:

1. An automatic latch for a drawhead key, said latch comprising an oscillable member having pivoted connection with said key, the axis of oscillation lying in the 20 length direction of the key, and said member having preponderance to one side of said axis.

2. The combination with a cross key for a drawhead; of a latch for said key, 25 trunnions on said latch, an aperture for the latch and bearing for said trunnions being provided in the key with their axis in the length direction of the key, the length of the latch being greater than the 30 height of the key seat, and preponderance being provided to one end of the latch.

3. The combination with a cross key for a drawhead; of a latch for said key, trunnions on said latch, an aperture for the latch and bearing for said trunnions being provided in the key with their axis in the length direction of the key, the length of the latch being greater than the height of the key seat, and preponderance being provided to one 40 end of the latch, the thickness of the ends of the latch corresponding to that of said key.

4. The combination with a cross key for a drawhead; of a latch for said key, trunnions on said latch, an aperture for the latch and bearing for said trunnions being provided in the key with their axis in the length direction of the key, the length of the latch being greater than the height of the key seat, the thickness of the ends of said latch 50 being substantially the same as that of said key, one end of said latch being dove-tailed in the plane of its sides to give preponderance to said last mentioned end and said aperture in the key being substantially of the same contour as that of the latch.

5. The combination with a cross key for a drawhead; of a latch for said key, trunnions

on said latch, an aperture for the latch and bearing for said trunnions being provided 60 in the key with their axis in the length direction of the key, the length of the latch being greater than the height of the key seat, the thickness of the ends of said latch being substantially the same as that of said key, 65 one end of said latch being dove-tailed in the plane of its sides to give preponderance to said last mentioned end and said aperture in the key being substantially of the same contour as that of the latch, and stops being formed on said key and said end to prevent the raising of that end beyond the top of said key.

6. The combination with a cross key for a drawhead having a key seat, of a latch for 75 said key, trunnions on said latch, an aperture for the latch and bearing for said trunnions being provided in the key with their axis in the length direction of the key, the length of the latch being greater than the 80 height of the key seat, the thickness of the ends of said latch being substantially the same as that of said key, one end of said latch being dove-tailed in the plane of its sides to give preponderance to said last mentioned end, said aperture in the key being of the same contour as that of the latch, stops being formed on said key and said end to prevent the raising of that end beyond the 85 top surface of said key, and a medially positioned tapered lug on each side of said latch providing greater thickness across said lugs than the height of said key seat.

7. The combination with a cross key for a drawhead having a key seat; of a latch for 95 said key, trunnions on said latch, an aperture for the latch and bearing for said trunnions being provided in the key with their axis in the length direction of the key, the thickness of the latch being greater than the 100 height of the key seat, and preponderance being provided to one end of the latch.

8. The combination with a cross key for a drawhead having a key seat, of a latch for said key, trunnions on said latch, an aperture for the latch and bearing for said trunnions being provided in the key with their axis in the length direction of the key, the length and thickness respectively of the latch being greater than the height of the key seat, 110 and preponderance being provided to one end of the latch.

In testimony whereof we affix our signatures.
